UNITED STATES PATENT OFFICE.

MATILDA A. KIRKWOOD, OF PITTSFIELD, MASSACHUSETTS.

WINDOW-CLEANING DEVICE.

Application filed February 25, 1927. Serial No. 170,996.

The purpose of my invention is to prevent the deposit of moisture, snow, etc., on window panes, and to remove such moisture, snow, etc., as may be deposited thereon. The 5 said invention is particularly adapted for use with windows, windshields, etc., as used in railroad locomotives, street cars, automobiles and the like, to keep the view thru same sufficiently unobstructed to permit of clear 10 vision for the operator of said vehicle.

With the above and other objects in view, I have provided an air blast for preventing the deposit of snow, moisture, etc., on the glass, the direction of said air blast being 15 such as to deflect the falling or floating moisture, snow, etc., from a path which would cause it to collide with the surface of said window, windshield, etc. over a predetermined portion of said surface which it is desired to protect from such deposit. For the 20 dissipation of such snow, moisture, etc., as may pass thru the above mentioned air blast and be deposited on the surface of said window, windshield, etc., as well as to prevent 25 the accumulation of moisture on the inner surface of said window, windshield, etc., I have provided a second air blast which is directed angularly against the outer surface of same and which is heated to a sufficient 30 temperature to insure evaporation of any deposited moisture before it shall have had time to collect in any considerable quantity.

I have also provided means for the control, manually, of the force, temperature and 35 location of said air blasts.

One method of accomplishing the above results is illustrated in the accompanying drawing in which:

Figure 1 is a front elevation of the air 40 blast nozzle.

Figure 2 is a sectional side elevation showing the device as installed in the vestibule of a street car.

Figure 3 is a section thru the nozzle as at 45 3-3.

Referring now in detail to the drawing by means of the numerals: 1 refers to a nozzle comprising a storage chamber 20 connected by means of passages 7, with a distributing 50 chamber 21, chamber 21 being provided with perforations 6. The object, and result, of this arrangement is to maintain a nearly uniform pressure at all of perforations 6. Perforations 6 are arranged in two groups, 55 one of which is angularly disposed with relation to the plane of the window pane 24,

against which the nozzle 1 bears, in such manner as to direct the air outwardly, away from surface of said window pane 24, the other group of perforations 6 is disposed 60 around the inner wall of nozzle 1 in a similar manner to the above mentioned group but disposed to the plane of window 24 in such a manner as to force a blast of air angularly against said surface. 65

Air is furnished to nozzle 1, thru tube 8 and flexible tube 9, by air compressor 10. The output of air compressor 10 bears such a relation to the combined areas of perforations 6 and the combined volumes of chambers 20 and 21 and tubes 8 and 9 as to insure a final temperature of the air (due solely to the work of compression thereof) sufficiently high to cause prompt melting of any snow deposited as well as evaporation of the moisture formed thereby or deposited directly. 70 75

The heat given up by the air blast also heats window pane 24 sufficiently to prevent deposit and condensation of any moisture on the inside of said window pane. 80

Air compressor 10 is driven by eccentric 12 in combination with compression spring 15 thru follower 13 and piston rod 14. The output of air compressor 10 is limited by means of adjustable stop lever 17 which is 85 manually controlled by means of rod 16 hand lever 18 and quadrant 19. Hand lever 16 is arranged to clamp to quadrant 19 and thus secure same in any desired position, thereby insuring a continuance of any desired air output and consequent pressure and temperature within the range of the device. The rod 16 is provided with a compression spring 25 which rests against the stop 26, and is held in position by means of the collar 90 27, which collar is rigidly secured to the rod 16. The purpose of the compression spring is to facilitate the upward motion of the rod 16. 95

Nozzle 1 is suspended before window pane 100 24 by means of rods 2 and nuts 23 and is provided with bosses 5 to insure sufficient space between said nozzle and window pane 24 to permit drainage of any condensed moisture or melted snow, etc. between them 105 as well as to permit a certain portion thereof to be blown thru same by the air blast. It is evident from the above that the position of nozzle 1 and consequently of the clear space on window 24 is adjustable in a vertical direction, by means of rods 2 and nuts 23, to suit the convenience of operators of 110

various heights, as well as to accommodate itself to either a standing or sitting posture on the part of the operator.

Having thus described my invention, what I claim as new and desire to secure by Letters Patent of the United States is:

1. In a device of the class described comprising a nozzle supported adjacent a window pane, said nozzle provided with a storage chamber connected with a source supplying fluid under pressure, means to direct the fluid into a distributing chamber adjacent the said storage chamber, means for adjusting the position of said nozzle in a vertical direction before said window pane.

2. In a device of the class described comprising a nozzle supported adjacent a window pane, said nozzle provided with a storage chamber connected with a source supplying fluid under pressure, means to direct the fluid into a distributing chamber adjacent the said storage chamber, said distributing chamber provided with a plurality of perforations leading therefrom, some of said perforations being angularly inclined towards the plane of said window, others being outwardly inclined angularly away from said window pane, means for adjusting the position of said nozzle in a vertical direction before said window pane, means for permitting the passage of moisture and other matter between said nozzle and said window pane.

3. In a device of the class described comprising a nozzle supported adjacent a window pane, said nozzle provided with a storage chamber connected with a source supplying fluid under pressure, said storage chamber connected at diverse points, by

means of perforations, with a distributing chamber, said distributing chamber provided with a plurality of perforations leading therefrom, some of said perforations being angularly inclined towards the plane of said window, others being outwardly inclined angularly away from said window pane, bosses attached to said nozzle and bearing against said window pane maintaining a definite space between it and said nozzle, means for adjusting the position of said nozzle in a vertical direction before said window pane.

4. In a device of the class described comprising a nozzle supported adjacent a window pane, said nozzle provided with a storage chamber connected with a source supplying fluid under pressure, a distributing chamber adjacent the said storage chamber, said distributing chamber separate and distinct from the said storage chamber and connected thereto by means of perforations at diverse points to permit a nearly uniform pressure of the fluid from the storage chamber into the distributing chamber, said distributing chamber provided with a plurality of perforations leading therefrom, some of said perforations being angularly inclined towards the plane of said window, others being outwardly inclined angularly away from said window, bosses attached to said nozzle and bearing against said window pane maintaining a definite space between it and said nozzle, means for adjusting the position of said nozzle in a vertical direction before said window pane.

In testimony whereof I affix my signature.

MATILDA A. KIRKWOOD.
